UNITED STATES PATENT OFFICE.

FRANCIS X. SCHULER, OF FORT WORTH, TEXAS.

INNER LINING AND REINFORCEMENT FOR PNEUMATIC TIRES.

1,408,644.

Specification of Letters Patent.

Patented Mar. 7, 1922.

Application filed August 18, 1921. Serial No. 493,419.

To all whom it may concern:

Be it known that I, FRANCIS X. SCHULER, a citizen of the United States, residing at Fort Worth, in the county of Tarrant and State of Texas, have invented new and useful Improvements in Inner Linings and Reinforcements for Pneumatic Tires, of which the following is a specification.

This invention relates to pneumatic tires and more particularly to an inner lining and reenforcement.

In the use of pneumatic tires, it is the custom to interpose a relatively thin sheet of leather, canvas, rubber or other similar material, such as an especially prepared sheet of fabric, between the casing and the inner tube. This interposed sheet of material creeps on the inner wall of the casing, resulting in undue wear, and because of the frictional resistance between the interposed sheet and the inner wall of the casing, the temperature of both the sheet and the casing is raised to such a point as to greatly shorten what is believed to be a much longer life of the casing. Moreover, these thin linings are forced by the air pressure within the inner tube into blowout fractures in the casing and thereby become torn or cut by the walls of such fractures. Both the casings and the inner tubes are expensive and how to prolong the life of both under working conditions has given the trade more or less concern, and especially since experiments have demonstrated the objectional features to be eliminated, there must be employed some means as will overcome same and yet not destroy the necessary resiliency which the tires must possess to satisfy easy riding conditions.

It is, therefore, one of the objects of my invention to provide a combined lining and reinforcement for use in the position between the casing and inner tube which embodies such characteristics that buckling of the interposed material is not possible, and wherein, possible creeping of the interposed material on the inner wall of the casing is prevented.

It is another object of my invention to provide a lining for use in the position between the casing and tube embodying among other characteristics, means for creating a vacuum between the interposed material and the casing to prevent creeping of the latter on the casing.

A still further object of the invention re-

sides in providing a relatively thick and strong lining for interposition between the casing and tube so as to aid in the prevention of punctures, and yet not destroy the requisite resiliency required in pneumatic tires.

With these and other objects in view, the invention consists in the novel construction, combination and arrangement of parts hereinafter fully described, illustrated in the accompanying drawings and pointed out in the claim hereto appended, it being understood that various changes in the form, proportion and minor details of construction, within the scope of the claim, may be resorted to without departing from the spirit or sacrificing any of the advantages of the invention:

Referring to the drawings:

Figure 1 is a fragmentary perspective view of the invention.

Figure 2 is a transverse sectional view.

Referring now more particularly to the accompanying drawings, the reference character 3 indicates an outer shoe or casing of any character, adapted for pneumatic tire purposes and the numeral 4 indicates an inflatable tube of any well-known make or variety.

My improved lining and reenforcement 5 is composed preferably of light quality pure gum so as to provide for necessary resiliency, and, as shown, it is substantially U-shaped in cross-section with its connecting web portion *a* between the sides *b* relatively thick. This thick portion *a* lies against the inner wall of the tread portion of the casing, strengthening the tread portion of the casing and aiding in the prevention of punctures as will be hereinafter explained. The thick portion *a* is substantially segmental in cross section and presents a plane or cylindrical inner surface to the inner tube which is flattened, as shown in Figure 2, before inflation so that the air pressure upon inflation will not excessively strain the inner tube which in inflation is distended from a flat condition to an approximately circular shape cross-sectionally resulting in the compression of the soft rubber segmental portion.

Pockets 6 are formed in the thick portion *a* of the lining 5, and extend over an area including the upper or outer side wall portions of the lining and are of a depth greater than their width, whereby under riding conditions, a vacuum is formed in the pockets to

cause the lining and reenforcement to hold firmly against creeping on the inner wall of the casing.

The results of the use of my lining and re-enforcement are; firstly, that creeping of the lining and reenforcement is prevented; secondly, that because of the thickness of the lining or reenforcement, punctures are obviated to a certain extent at least, in that certain 10 length nails and other articles in passing through the casing are prevented from reaching the tube; thirdly, the thickness of the lining and reenforcement is such as to prevent buckling and consequent bulging of the inner 15 tube into fractures of the casing and becoming torn or cut as is often the case where the linings and supposed reenforcements are relatively thin; fourthly, while the lining and reenforcement is relatively thick, the requisite resiliency of the pneumatic tire is not 20 destroyed; and fifthly, the thickness of the lining and reenforcement is such as to permit the use of a smaller tube for a casing ordinarily requiring the use of a larger tube, 25 thereby reducing expense, as regards the

upkeep of tires for the reason that the smaller the tube the less it costs.

What is claimed is:

A lining for use between the casing and the inner tube of a pneumatic tire, including 30 a light quality gum and relatively thick segmental portion presenting an inner cylindrical surface to the inner tube and flattening the same beneath the tread of the tire prior to the inflation of the inner tube into approximately circular form to permit the required air pressure to be applied to the inner tube without excessive strain or distension of the material thereof and to produce the compression of the segmental portion, said 40 segmental portion being provided in its outer surface with cross sectionally small radially arranged air pockets adapted to create a vacuum between the lining and the casing to prevent creeping of the lining on the 45 casing.

In testimony whereof I have hereunto set my hand.

FRANCIS X. SCHULER.
